UNITED STATES PATENT OFFICE.

JOHN C. TELLER, OF MINNEAPOLIS, MINNESOTA.

FURNACE.

1,044,946.

Specification of Letters Patent. Patented Nov. 19, 1912.

Application filed August 21, 1909. Serial No. 514,035.

To all whom it may concern:

Be it known that I, JOHN C. TELLER, of Minneapolis, Hennepin county, Minnesota, have invented certain new and useful Improvements in Furnaces, of which the following is a specification.

The object of my invention is to provide for the more perfect combustion of fuel and the prevention of discharge of smoke from the furnace stack.

A further object is to increase the efficiency of the furnace by providing means whereby a more rapid and complete consumption of the gases will be obtained.

The invention consists generally in various constructions and combinations, all as hereinafter described and particularly pointed out in the claims.

In the accompanying drawings, forming part of this specification, Figure 1 is a longitudinal sectional view through the furnace, illustrating the relative location of the air ports in the arch or baffle wall and in the top of the bridge wall proper, Fig. 2 is a transverse sectional view, illustrating the position of the air flues in the top of the furnace leading to the arch or baffle wall, Fig. 3 is a perspective view, illustrating the block or tile, which forms the top of the bridge wall, Fig. 4 is a front elevation, Fig. 5 is a fragmentary view of the furnace floor.

In the drawing, 2 represents a boiler having a front 3, and 4 the top of a furnace, which preferably projects forwardly in front of the boiler, corresponding substantially in form to a Dutch oven. This furnace top has an arch or baffle wall 5 and a series of air flues 6 leading from the forward end of the furnace top through the arch or baffle wall, and admitting currents of air into the combustion chamber 7 beneath said top. 8 is a grate beneath which is the ash pit 9 and 10 is a bridge wall in the rear of the grate and ash pit supporting a tile block 11. This block has a chamber 12 therein communicating with any desired number of air flues 13, one of which is illustrated in Fig. 1 and which extend horizontally through the floor 14 beneath the boiler, terminating in the wall 15, which has a flue 16 extending transversely of the boiler and communicating with the open air. Through this flue 16, air is admitted to the flues 13 and heated during its passage therethrough and permitted to expand in the chamber 12, which acts as a reservoir for the air supply. The block 11

has a series of narrow slots 17, arranged in its upper wall in position to direct the currents of air across the throat 18, which is formed between the block 11 and the arch or baffle wall. The currents of air from the arch or baffle wall and the chamber 12 will meet and mingle in this throat and mix with the gases and products of combustion from the chamber 7 and cause a more rapid and complete combustion of the same. The effect of this combustion will be to raise the temperature of the chamber 19 beneath the boiler 2 and greatly increase the efficiency and capacity of the boiler. It will be noted that the entire under surface of the boiler is exposed to the heat of these burning gases and consequently a great economy in fuel will be effected and the discharge of black smoke from the stack avoided.

The volume of air admitted to the bridge wall and arch or baffle wall flues may be regulated, according to the character of the fuel used and the condition of the fire, so that the proper amount of air will be mixed with the hot gases before entering the chamber beneath the boiler.

I claim as my invention:

1. The combination, with a boiler, and a chamber beneath the same, of a furnace having a combustion chamber and grate, the top of said furnace having a horizontal air flue therein extending from the front thereof toward the rear, said top having an inverted arch or baffle wall at its rear end with a port therein communicating with said air flue and said combustion chamber having a bridge wall and a block thereon, a narrow throat or passage being formed between said block and said arch or baffle wall at the front of the boiler and leading to the chamber beneath the boiler, said block having ports therein diagonally opposite the port in said arch or baffle wall, and a floor arranged beneath said boiler and having a series of flues communicating with the ports in said bridge block and through which flues air is admitted to said block, and the ports of said bridge block and arch or baffle wall directing the currents across said throat and causing them to mingle with the products of combustion passing therethrough, substantially as described.

2. The combination, with a boiler, of a furnace setting having a horizontal top provided with a series of air flues, and an arch

or baffle wall having ports communicating with said flues, said arch or baffle wall being located beneath the forward end of said boiler, and a chamber being formed in the rear of said arch beneath said boiler extending to the rear of the boiler, said furnace having a combustion chamber and grate, and a bridge wall in the rear of said grate, a chamber being formed in the upper part of 10 said bridge wall having ports diagonally opposite the ports of said arch or baffle wall and separated therefrom by a throat or passage which communicates with said combustion chamber and with the chamber beneath 15 said boiler, a floor provided beneath said boiler chamber and having a series of flues provided with air intake openings and communicating with the chamber in said bridge wall, the air passing through the flues in said floor being heated and expanding upon entering said chamber, and flowing out through the ports thereof and mingling with the products of combustion and with the air from said arch or baffle wall.

25 3. The combination, with a boiler and chamber beneath the same, of a furnace having a combustion chamber and

grate, said combustion chamber having a depending arch or baffle wall and a bridge wall at its rear end at the front 30 of the boiler, a narrow throat or passage being formed between said bridge wall and said arch or baffle wall and leading to the chamber provided beneath the boiler, said bridge wall having ports therein opposite 35 the lower portion of said arch or baffle wall, a floor forming the bottom of said chamber beneath said boiler and having a series of air intake flues communicating with the ports in said bridge wall, and said ports directing the currents of air from said flues across said throat toward said arch or baffle wall at the rear of the furnace and front of the boiler and causing the said currents to mingle with the products of combustion in 45 said throat or passage, substantially as described.

In witness whereof, I have hereunto set my hand this 13th day of August 1909.

JOHN C. TELLER.
